UNITED STATES PATENT OFFICE

ROBERT W. McCREEERY, OF NEW YORK, N. Y.

COLLAR AND METHOD OF MAKING THE SAME

Application filed May 18, 1931. Serial No. 538,033.

My invention relates to a new and improved collar.

One of the objects of my invention is to provide a soft or unstarched collar which may be detached, or which may be attached to a shirt. Although my invention is particularly useful in connection with a soft or unstarched collar, it is not necessarily limited to this type of collar, as it may also apply to a starched collar.

Another object of my invention is to provide a collar consisting of a neckband, and a front or outer portion, one of said members, such as the front of the collar, being constructed so that a natural line of fold is provided between the two members of the collar.

Another object of my invention is to provide a collar having a stiffening member or lining, which is preferably although not necessarily, located in the front of the collar, this stiffening member or lining being so shaped and constructed as to provide a natural or definite line of fold between the two members of the collar. This stiffening member is made of fabric which produces the shape or body of the collar.

Other objects of my invention will be set forth in the following description and drawings, which illustrate a preferred embodiment of my invention, it being understood that the above general statement of the objects of my invention is intended to generally explain the same and not to limit it in any manner.

Fig. 1 is an elevation showing the construction of the front or top of the collar.

Fig. 2 is a sectional view through the line 2-2 of Fig. 1.

Fig. 3 is an elevation showing the three layers of the front or the top of the collar after said layers have been turned, in order to complete the first operation in the process of making the collar.

Fig. 4 is a sectional view on the line 4-4 of Fig. 3.

Fig. 5 is an elevation showing the front or the top of the collar after additional sewing operations have been completed.

Fig. 6 is a sectional view on the line 6-6 of Fig. 5.

Fig. 7 is an elevation showing the assembly of the top or the front of the collar, with the back or neckband of the collar.

Fig. 8 is a sectional view on the line 8-8 of Fig. 7.

Fig. 9 is an elevation showing the final relation between the top of the collar and the neckband of the collar.

Fig. 10 is a sectional view on the line 10-10 of Fig. 9.

The front or top of the collar is preferably made of three layers of fabric, namely, a back layer 1, a front layer 2, and a lining L.

When the collar is finally assembled, the back layer 1 of the top of the collar is adjacent the neckband of the collar, and the front layer 2 forms the face layer of the front of the collar. The layers 1 and 2 can be made of any suitable fabric, such as a woven cotton or woven silk fabric, or the like, and the collar may be made either soft or starched. The lining L can be made of any suitable fabric, which imparts the necessary stiffness to the collar. This lining L can be made of heavy cotton material, but it is preferably made of wool, since wool is relatively non-crushable and wrinkle-proof.

In the first operation the three layers of the top of the collar are assembled as shown in Fig. 2, the rear layer 1 being then adjacent the front layer 2, and the lining L being then adjacent the front layer 2. These three layers are connected by stitches S, which extend along three sides of the said three layers, so that the fourth side, namely, the top side shown in Fig. 1 is free from said stitches. This forms a pocket-like structure, and the next operation is to turn this inside out, thus producing the structures shown in Figs. 3 and 4. It is very easy for the operator to turn the edges of the three layers around the line of stitches S, so that it is not necessary to use a turning machine.

It will be noted that the lining or stiffening layer L is of less width than the outside layers 1 and 2. Likewise, it is to be understood that the lining L can be made of any desired material, and this material is not necessarily stiffer than the material of the outside layers 1 and 2. Hence, the lining material per se is

bendable, save as it is reinforced by a plurality of thicknesses. Referring to Fig. 10, the entire portion of the front member of the collar which is above the line of stitches S_a is 5 readily bendable, because of the single thickness of the member L . The upper edge of the member L projects only very slightly above the lines of stitches S_a , thereby not impairing the flexibility of the front member 10 at this point.

The next operation is to sew the rear layer 1 and the lining L by another row of stitches S_a , this row of stitches being invisible at the front layer 2 so that it does not mar the 15 appearance of the collar.

As shown in Fig. 3, the line of stitches S_a is shorter than the length of the layers 1, 2 and L . Said layers 1, 2 and L have substantially the same length. The line of stitches 20 S_a is curved, in order to impart a suitable curved contour to the collar, and to cause it to conform naturally to the shape of the neck.

The next operation is to connect the three layers of the top of the collar by means of 25 another line of stitches S_b , which extend around three sides of the assembled layers, as shown in Fig. 5.

This operation leaves the fourth or top side 30 of the assembled layers open, as shown in Figs. 5 and 6.

It will also be noted that the stitched edges of the three layers 1, 2 and L have been turned by the operations previously specified, in order to produce neat edges.

35 The front or top F of the collar now has the back or neckband B assembled therewith.

The back or neckband B comprises outer layers $1a$ and $2a$, which correspond to the layers 1 and 2, and the back B also includes a 40 lining L_a , which corresponds to the lining L which has been previously specified.

However, in making the back of the collar the three layers $1a$, $2a$ and L_a are made of the same shape and dimensions throughout.

45 In order to assemble the three layers of the back B , the layers L_a and $2a$ are placed upon the layer 1, so that the layers $2a$, L_a and 1 are substantially coincident. The layer $1a$ is likewise laid upon the layer 2, so that said 50 layers $1a$ and 2 are also substantially coincident. The three layers of the back B are then united to the layers 1 and 2, by means of stitches S_c , and it will be noted that these 55 stitches S_c do not pass through the lining L , due to the fact that the lining L is of less width than the outer layers 1 and 2. The three layers of the back B are then turned into the position shown in Fig. 8, and the three layers of the back B are again connected 60 to the outer layers 1 and 2, by means of a line of stitches S_d .

As shown in Fig. 7, the stitches S_d extend either partially or wholly to the free edge of the back B . The back B is then turned into 65 the position shown in Fig. 9. This turning

causes the edges of the layer L_a to be turned around the line of stitches S_d . While the layers L and L_a may have the same contour as the outer layers of the collar, I do not wish to be limited to this identity of contour. The lining layers are made of fabric which substantially imparts the body or shape to the collar. According to my invention, the relatively heavy lining fabric is turned simultaneously with the outer layers of the 75 collar, so that wrinkling is eliminated.

If the collar is to be attached to a shirt, the free edge of the back B is suitably connected to the shirt. If the collar is to be used as a separate collar, the free edge of the back B 80 is suitably finished.

As shown in Fig. 10, when the collar is completely assembled and ready for use, the lining strip L_a extends above the lining strip L , and the collar has an intermediate fold 85 portion of greater yieldability than either the top or the neckband of the collar. This causes the collar to naturally retain the shape shown in Fig. 10, so that the front or top of the collar does not creep upwardly. Referring to Fig. 8 of the drawings herein, it will be noted that the front of the collar consists of only two layers adjacent the line of fold. Fig. 10 shows that the folded top part of the front of the collar consists of only two layers 90 of fabric, and the lining does not extend into the folded part. Likewise the strip L only has a single thickness below the folded part, because the top edge of the lining strip L is non-turned. The elimination of the bulge 95 which would be produced by the inturned top edge of the strip L , permits the neckband of the collar to lie flat against the front of the collar as shown in Fig. 10. Likewise, the collar can be bent around the neck and sufficient space is left for the necktie, because the 100 folded part of the top of the collar is free from stiffening material, and the upper edge of the lining of the front of the collar is non-turned. Likewise, the folded part of the collar is free from the front lining layer L and the rear lining layer L_a and extends substantially to the top of the collar.

As shown in Fig. 10, the front of the collar has the top thereof thinner than the bottom thereof. Since the stiffening members L and L_a are turned simultaneously with the outer layers of the collar, the assembled collar is free from wrinkles. Due to the construction 110 of the collar, a starched collar can be ironed flat, and it is not necessary to turn the neckband over on the front of the collar by the usual turning machine.

I have shown a preferred embodiment of 115 my invention, but it is clear that numerous changes and omissions can be made without departing from its spirit.

For example, the lining strips may be made 120 of mohair because mohair fabric is very resilient and wrinkle-proof and is superior to ordinary wool in these respects. Likewise,

the lining may consist of a composite fabric having a mohair warp and a cotton filler thread. If desired, the lining may have cotton warp threads and mohair filler threads.

5 I claim:

1. A collar having a front member and a neckband, said front member having a folded upper end portion to which the neckband is connected, said front member and said neckband each consisting of outer layers of fabric and an intermediate lining layer, the top edge of the lining of the front member being below the folded portion of the front member so that said folded portion of the front member is free from said lining, the lining of the neckband extending substantially to the upper edge of the collar, the upper edge of the lining of the front member being of single thickness and being connected to the front member by a line of stitches, the entire portion of said front member which is above said line of stitches being readily bendable.

2. A collar having a front member and a neckband, said front member having a folded upper end portion to which the neckband is connected, said front member and said neckband each consisting of outer layers of fabric and an intermediate lining layer, the top edge of the lining of the front member being below the folded portion of the front member so that said folded portion of the front member is free from said lining, the lining of the neckband extending substantially to the upper edge of the collar, the upper edge of the lining of the front member being of single thickness and being connected to the front member by a line of stitches, the entire portion of said front member which is above said line of stitches being readily bendable, the other edges of the lining of the front member being turned along lines of stitches which secure said lining of the front member to the front member.

3. A collar having a front member and a neckband, said front member having a folded upper end portion to which the neckband is connected, said front member and said neckband each consisting of outer layers of fabric and an intermediate lining member connected thereto by means of stitches, the top edge of the lining of the front member being below the folded portion of the front member so that said folded portion of the front member is free from said lining, the lining of the neckband extending substantially to the upper edge of the collar, the stitches of the neckband being above the stitches of the front member.

60 In testimony whereof I affix my signature.
ROBERT W. McCREEERY.
